FOREIGN PATENT DOCUMENTS

DE 10144520 3/2003

Primary Examiner — Garth Rademaker*Assistant Examiner* — Fitzgerald L Butac(74) *Attorney, Agent, or Firm* — Brooks Kushman P.C.(57) **CLAIM**

The ornamental design for a fixture bar clamp, as shown and described.

DESCRIPTION

FIG. 1 is a top perspective view of the fixture bar clamp;

FIG. 2 is a bottom perspective view thereof;

FIG. 3 is a top plan view thereof;

FIG. 4 is a left side elevation view thereof;

FIG. 5 is a bottom plan view thereof;

FIG. 6 is a right side elevation view thereof;

FIG. 7 is a distal end elevation view thereof; and,

FIG. 8 is an inside end elevation view thereof.

The broken line directly adjacent to shaded portions illustrates the bounds of the claimed design. All other broken lines illustrate portions of the fixture bar clamp. None of the broken lines form any part of the claimed design.

1 Claim, 2 Drawing Sheets(56)
